DESCRIPTION

USPC D6/545, 515, 518-523, 542, 543-544; D3/201; D9/688, 690, 694; D10/74, D10/103, 122; D14/371; D28/10; 206/225, 233, 389, 391, 407, 409; 211/13.1, 45, 59.2, 85.5; 221/26, 33, 221/282-283, 92, 97; 222/14, 105, 146.3, 222/173, 180, 181.1, 181.2, 181.3, 251, 222/628; 248/905; 242/570, 590, 159, 242/160.2, 550, 560, 594, 59, 588, 598, 242/598.3, 598.65

FIG. 1 is a front/right/top perspective view of a dispenser (a front/left/top perspective view would be a mirror image thereof);

CPC A47K 2005/1218; A47K 5/12; A47K 5/1205; A47K 5/1211; A47K 5/14; A47K 5/1202; A47K 2210/00; A47K 5/1215; A47K 5/1204; A47K 7/028; B05B

FIG. 2 is a rear/left/bottom perspective view thereof (a rear/right/bottom perspective view would be a mirror image thereof);

FIG. 3 is a front elevational view thereof;

FIG. 4 is a right side elevational view thereof; and,

FIG. 5 is a top plan view thereof.

The broken lines in the drawings depict environmental subject matter only and form no part of the claimed design.
